ELECTRONIC COUNTER INDICATOR PANEL

James P. Donovan, Louisville, Ky., assignor to General Equipment and Manufacturing Company, Inc., Louisville, Ky., a corporation of Kentucky

Filed Mar. 25, 1968, Ser. No. 11,123

Term of patent 14 years

Int. Cl. D14—02

U.S. Cl. D26—5

FIG. 3

FIG. 1

FIG. 2

FIGURE 1 is a front perspective view of an electronic counter indicator panel, showing my new design.

FIGURE 2 is a front elevation of the new indicator panel.

FIGURE 3 is a vertical section taken along the line 3—3 of FIGURE 2.

The broken line showing of the housing in FIGURE 1 is depicted for illustrative purposes only.

I claim:

The ornamental design for an electronic counter indicator panel, as shown and described.
